UNITED STATES PATENT OFFICE.

FRANK BURRIDGE, OF MARSTON, NEAR NORTHWICH, ENGLAND.

GLARE-PREVENTING DEVICE FOR LAMPS.

Application filed November 2, 1921. Serial No. 512,347.

To all whom it may concern:

Be it known that I, FRANK BURRIDGE, a subject of the King of England, residing in Marston, near Northwich, Cheshire, England, have invented certain new and useful Improvements in Glare-Preventing Devices for Lamps, of which the following is a specification.

This invention has for its object to provide an improved construction of device for eliminating glare from motor road vehicle lamps and the like, that is to say for controlling the beam of light from such a lamp so as to direct it on to the ground, or otherwise as desired, and to prevent it spreading upwards to such a height that it shines in the eyes of other road users; obviously, the device can be used for preventing glare in other circumstances as well.

The invention relates to glare-preventing devices of the type in which there are provided a number of parallel blades set edge-wise in the beam so as to limit any tendency of the beam to spread. Such devices have been made for the vehicle head-lamps in which the blades aforesaid are set horizontally and have their under sides polished and their upper sides blackened. Any light tending to spread upwards is therefore reflected downwards, and any light tending to spread downwards is absorbed by the blackened surface of the blades and is not reflected upwards so that the light is directed mainly parallel with the blades with a small portion reflected downwards on to the road surface. According to this invention there is provided a glare-preventing device of the type above described wherein the blades are mounted in a detachable frame which frame is so shaped as to be located within the body of the lamp immediately behind the glass and in front of the reflector. In this way the device is suitable for fitting to any existing lamp and does not require, as has heretofore been the case, the fitting of a new front and glass to the lamp.

According to a further feature of this invention the device comprises a thin flat arcuate or annular member adapted to fit against the front edge of the reflector in the small space available between it and the glass, and flat plate-members are mounted on the arcuate member at right-angles to its plane so as to project into the reflector, these plate-members extending as chords across the arcuate member and being slotted

from one edge to receive the parallel light-controlling blades.

According to yet another feature of the invention the blades aforesaid are made very thin and are set very close together; dimensions which have proved suitable in practice being blades 0.006 inch thick spaced 0.05 inch apart.

In the accompanying drawings which illustrate one embodiment of this invention—

Figure 1 is a front elevation of the device to be fitted to a lamp;

Figure 2 is a section on the line 2—2 of Figure 1, showing the device in a lamp; and

Figure 3 is a plan of Figure 1.

Like reference characters indicate like parts throughout the drawings.

The frame of the glare-preventing device comprises two arcuate members 10, 11 shaped and spaced apart to lie on a circle which will fit within the largest part of the body of the lamp as shown in Figure 2. These members are conveniently stamped out of sheet material so that the thickness as shown in Figure 3 is small. These members 10, 11 are thereby adapted to lie within the comparatively narrow space between the end flange 12 of the reflector of the lamp and the opposed inner flange 13 of the front.

The members 10, 11 are provided with slots 14 which are spaced apart so that they can be engaged by the screws 15 which are ordinarily used for securing the reflector 16 in the body 17 of the lamp.

The two members 10, 11 are connected together by plate-like members 18, 19 which stand at right-angles to the plane of the members 10, 11 as shown most clearly in Figures 2 and 3. These plate members may be stamped out of sheet material integrally with the members 10, 11, or they may be separately formed and rigidly secured thereto in any desired manner. The members 18, 19 project rearwardly from the plane of the members 10, 11 so as to lie within the reflector 16 of the lamp. The ends of these members are therefore cut away as shown at 20 to be accommodated within the conical part of the reflector.

The plate members 18, 19 are each slotted from their rear edge 21 to a convenient depth, say about half the width of the members, as shown at 22, and the light-controlling blades 23 are inserted in these slots. The blades 23 themselves are each slotted from their forward edges so that when in-

5 serted into the slots aforesaid in the plate members 18, 19, their slots can engage the unslotted portions of the plates. The rear edges of the blades 23 preferably project 10 slightly beyond the rear edges of the plate members 18, 19, as shown at 24, and they are all firmly secured in place by a wire or the like 25 which is secured at each end to an end of a plate member 18, 19, as by 15 soldering, or in any other desired way, and extends over the edges of the blades 23.

The lengths of the blades are graduated as shown in Figures 1 and 3 so that the overall dimensions and shaping of the device conform to the circular formation of the lamp wherein it is to be fitted.

As above stated, a feature of the invention is that the blades which are used in this device are thinner and set closer together than has hitherto been the practice in such a device. If desired the upper surface of each blade may be blackened to prevent any reflection of light upwards from their surfaces, and the under surfaces may 25 be left bright to reflect light downwards.

This invention therefore provides a device which is adapted to be fitted to any existing lamp without alteration of the lamp itself, and the device effectively limits the upward spread of the light from the axis of the reflector. By setting the blades with their plane parallel with the axis of the reflector, it is ensured that the beam of light will not diverge upwards from the 30 axis of the reflector, and by suitably inclining the lamp the beam may be directed in a horizontal direction or downwards as may

be desired. The lateral spreading of the light however is not materially changed so that the desirable lighting, of a beam concentrated on the road at a considerable distance ahead and a local lateral lighting of less intensity in the immediate neighborhood of the lamp, can be readily obtained.

What I claim as my invention and desire to secure by Letters Patent is:—

In an anti-glare device for vehicle lamps having a forwardly presented and circumferentially extending face situated behind the glass of the lamp, the combination of two vertical plates spaced apart and extending rearwardly from the plane of said face so as to project edgewise into the lamp, a series of horizontally disposed and closely spaced parallel strips of thin material mounted upon said vertical plates, said plates being interlocked with said strips by means of slots in the plates interengaging with cooperating slots in the strips and retaining wires attached to the top and bottom of said vertical plates and extending down the rear edges of said strips so as to retain them in position upon said vertical plates, and two oppositely disposed flat arcuate attachment members of thin strip material connected to said vertical plates at the opposite ends thereof so as to extend only partially around and be secured to the said forwardly presented face of the lamp, substantially as described.

In testimony whereof I affix my signature.

FRANK BURRIDGE
